UNITED STATES PATENT OFFICE.

RUSS J. CHRISTY, OF FREMONT, OHIO, ASSIGNOR TO THE CHRISTY KNIFE COMPANY, OF SAME PLACE.

KNIFE.

SPECIFICATION forming part of Letters Patent No. 508,916, dated November 21, 1893.

Application filed May 15, 1893. Serial No. 474,250. (No model.)

To all whom it may concern:

Be it known that I, RUSS J. CHRISTY, residing at Fremont, in the State of Ohio, have invented certain new and useful Improvements 5 in Knives and Similar Tools, of which the following is a specification, reference being had therein to the accompanying drawings.

This invention relates to knives, saws, and articles of cutlery of similar character.

10 The object of the invention is to produce a knife primarily intended for household use, in which a very thin or flexible blade may be kept strained and rigid; also to produce a cutting tool with a thin blade, in which the straining bow may act as a gage in cutting; also to produce a blade with a straining bow and handle made integral, so as to give a maximum of strength and minimum of cost; also to improve tools of the character described in various particulars.

Figure 1 is a side or face elevation of a knife or tool made according to this invention. Fig. 2 is a plan or back view. Fig. 3 is a view of the opposite side of Fig. 1. Fig. 25 4 is an end elevation, and Fig. 5 is a section of the blade. Fig. 6 is a side elevation of a blade with a modified handle. Fig. 7 is a face elevation of a blade with still another modification of handle, and Fig. 8 is an edge view 30 of the tool Fig. 7. Fig. 9 is a detail section of the wire or bar passed through the hole in the blade.

A, indicates the blade. This blade is narrow and very thin, preferably of tempered 35 steel, and has a serrated edge. The bevel is entirely on one side of the blade, and the teeth and interdental spaces are both sharpened, preferably as in my Patent No. 460,677, of October 6, 1891, but not necessarily so.

40 The handle B, is made from a single piece of drawn metal or wire, which may have a transverse slot B' at the end which embraces the blade, or it may be otherwise secured to the blade, for instance as in my Patent No. 414,973, of November 12, 1889. The handle is formed by a loop or return bend of the wire, and after returning nearly to the end of the blade, the wire bends to one side, and then extends, as at B², nearly to the other end of 45 50 the blade in a direction about parallel with the plane in which the body of the blade lies,

but not necessarily parallel with the back or edge of the blade. This bar B² serves as a straining bar to hold the blade straight and stiff, and also as a gage or guide in cutting 55 with the knife, especially if it be used as a bread, cake, or meat knife. The gage bar B² need not rest against the slice of bread or meat in cutting, but is a ready guide to the edge in cutting straight slices. So if the tool 60 be used as a saw, the bar B² answers as a guide. The blade enters between the slice and the gage bar B², and the gage bar prevents the slice from falling over until it is entirely severed from the loaf or mass. 65

As shown in Fig. 6, the gage bar B² may be bowed upward, so as to act as a spring throughout its entire length.

The end of the gage or straining bar B² is turned toward the blade, and passes through 70 a hole in the blade. The bar is notched near the end. The end of the bar is such that the end B³ has to be sprung in a little toward the handle to pass it through the hole in the blade. The spring of the bar not only holds the blade 75 firmly to the bar, but puts the blade under strong tension to hold it straight or taut. As shown in the drawings, practically the entire bar, including the handle, becomes a part of the straining bar. The ends of the blade are 80 attached near to the ends of the straining bar, and the loop or return bend which forms the handle also forms part of the stretcher or straining bar.

The flat or plane face of the blade is pref- 85 erably away from the gage bar, so that the blade may be kept sharp by grinding on this plane face without hinderance from the gage bar.

In Figs. 7, and 8, the end of the handle bar 90 is passed through a hole in the blade, and the ends of the bar have a plurality of notches, so that the blade may be placed at different distances from the gage bar B², and both ends be held by straining the blade into the notches 95 in the bar. See sectional detail, Fig. 9.

The skilled mechanic will understand that a very strong handle and gage may be made from a single piece of wire, and that the elasticity of tempered wire, when bent into about 100 the form described, or other forms of the same general character will keep the blade under

strain. In this way an exceedingly thin blade may be used, so that a clean cut may be made with little resistance, and yet all necessary rigidity can be had, in the same manner as is had in the bow saw or sash saw, not from the blade but from the supporting bar, which as has been described also acts as a gage bar.

The grinding of the knife can be effected on a flat faced grindstone, if the bevel be all on one side, and the plane side be turned away from the gage bar.

I do not limit my invention to the precise constructions shown in the drawings.

What I claim is—

15 1. The knife described consisting essentially of a serrated blade, and an elastic straining bar attached near its ends to the ends of said blade, the handle being a return bend or loop in said bar, and a part of the bar extending in a plane about parallel with the plane of the blade, substantially as described.

20 2. The knife having a thin flexible blade, and an elastic straining bar extending along-

side said blade in a plane about parallel therewith, said blade adjustably secured to said bar, substantially as described.

3. The straining bar at the side of the blade, having a portion near one end notched and extending about at a right angle to the blade and through a hole therein, said blade and bar being connected at the handle end, substantially as described.

4. The knife described, consisting essentially of a thin, flexible, serrated blade, having holes near the ends, and the straining bar 35 and handle, in one piece of elastic metal, the handle consisting of a return bend or loop in the bar, the ends of said bar extending through holes in the blade, all substantially as described.

In testimony whereof I affix my signature in presence of two witnesses.

RUSS J. CHRISTY.
